UNITED STATES PATENT OFFICE.

JOSEPH A. RICARD, OF BOSTON, MASSACHUSETTS.

SAFETY-PLUG FOR BOILERS.

1,159,710.

Specification of Letters Patent.

Patented Nov. 9, 1915.

Application filed December 26, 1914. Serial No. 879,413.

To all whom it may concern:

Be it known that I, JOSEPH A. RICARD, a citizen of the United States of America, and a resident of Boston, in the county of Suffolk and State of Massachusetts, have invented certain new and useful Improvements in Safety-Plugs for Boilers, of which the following is a specification.

This invention relates to safety devices for steam boilers and the like in which a fusible plug is adapted to be blown out at a predetermined low water level and has for its object the production of a device of this character in which a new plug may be quickly inserted.

The invention consists of a valved outer member secured to a boiler and having threaded thereto an inner member provided with a passage normally closed at its inner end by a fusible plug and having a valve at its outer end adapted to be closed when the fuse has blown out and to remain closed until the inner member has been adjusted relatively to the outer member sufficiently to permit the closing of the valve in the outer member.

The invention further consists in certain novel features of construction and arrangement of parts which will be fully understood by reference to the description of the drawings and to the claims hereinafter given.

Of the drawings: Figure 1 represents a plan of a device embodying the principles of the present invention. Fig. 2 represents a longitudinal section of the same. Fig. 3 represents a plan of the same with the parts adjusted relatively to each other sufficiently to permit the closing of the valve in the outer member. Fig. 4 represents a longitudinal section of the same, and Fig. 5 represents a perspective of the fusible plug.

Similar characters designate like parts throughout the several figures of the drawings.

In the drawings, 10 is a tubular member provided at one end with an external thread 11 by which it may be secured to a boiler, the opposite end of said member being provided 50 with an internal thread at 12 to receive the threaded portion of an inner tubular member 13. Intermediate the ends of the member 10 is a valve 14 having a cylindrical opening 15 extending transversely thereof

in alignment with the axis of the bore of 55 said member 10.

The valve 14 is operable by means of the handle 16. The diameter of the cylindrical opening 15 in the valve 14 corresponds to that of the cylindrical portion 17 of the bore 60 of said outer member 10. At the extreme inner end of the member 10 is a reduced cylindrical passage 18 forming a shoulder 19 as indicated in Figs. 2 and 4 of the drawings.

The inner member 13 is provided with a tubular extension 20 fitting the cylindrical portion 17 of the bore of the outer member and also fitting the opening 15 through the valve 14. The outer end of the tubular 70 member 13 is provided with a valve 21 operable by the handle 22.

The bore 23 of the extension 20 is adapted to receive the shank 24 of a fusible plug 25, as indicated in Fig. 2 of the drawings, said 75 plug being shown by itself in Fig. 5 of the drawings. When the device is in use the threaded end 15 is secured into the casing of the boiler, the passage 18 communicating with the interior thereof. Obviously the device is secured to the boiler at the extreme low water level. The valve 14 is in the position shown in Fig. 2 with the extension 20 extending through the opening 15 in said valve and the member 13 is so adjusted relatively to the outer member 10 that the fusible plug 25 will be jammed against the shoulder 19 effectually closing the outlet from the boiler. The valve 22 will be in open position at this time. As long as the 90 water in the boiler is above the passage 18 the device will be inoperative and no leakage from the boiler will be permitted.

As soon as the water in the boiler is lowered sufficiently to uncover the passage 18 95 the steam will melt the fusible plug 25 and this plug being removed, there will be a clear passage for the escaping steam. This escaping steam will call the attention of the operator to the fact that the water in the 100 boiler is at an unsafe level. The operator then turns the valve 21 by means of the handle 22 into the position indicated in Figs. 3 and 4, preventing further escape of steam. The inner member 13 is then turned, the threads 12 105 causing it to be moved longitudinally relatively to the outer member 10. This operation is continued until the extension 20 has

been removed from the opening 15 in the valve 14, which is then closed by moving the handle 16 into the position indicated in Figs. 3 and 4 of the drawings. This closing 5 of the valve 14 prevents any escape of the steam through the outer member 10 and makes it possible to entirely remove the inner member 13 and insert the shank 24 of a new fusible plug 25 into the end of the bore 10 23. The member 13 is then replaced into the outer member 10 and screwed therein until the fusible plug 19 reaches a point adjacent to the valve 14, at which time the valve 21 must be in closed position. The valve 14 15 may then be moved into open position and the inward movement of the member 13 continued until the new fusible plug 25 is forced into contact with the shoulder 19 in the outer member 10. The valve 21 will then be 20 opened and the entire device will be in condition to again indicate any unsafe condition 25 of the water in the boiler that may occur.

This makes a very simple device for the purpose designed, which is simple in its operation and very effective in use. By such a construction as is herein shown the fusible plugs 25 may be reinserted very quickly.

The many advantages of this device it is believed will be fully understood from the foregoing description.

Having thus described my invention, I claim:

1. In a device of the class described, the combination of an outer tubular member; a 35 valve therein the axis of which is perpendicular to the axis of said tubular member; an inner tubular member threaded to said outer member and provided with an extension normally extending through a trans- 40 verse opening in said valve; a fusible plug in the inner end of said extension; and a valve in the inner tubular member.

2. In a device of the class described, the combination of two tubular members, one 45 within and movable relatively to the other; a valve in each member with their axes perpendicular to the axis of said tubular members; a cylindrical extension on the inner member normally extending through a 50 transverse opening in the valve of the outer member; and a fusible plug in the end of said extension.

3. In a device of the class described, the combination of two tubular members, one 55 within and movable relatively to the other which is provided with an internal shoulder; a valve in each member with their axes perpendicular to the axis of said tubular members, a cylindrical extension on the inner member normally extending through a 60 transverse opening in the valve of the outer

member; and a fusible plug in the end of said extension normally abutting said internal shoulder of the outer member.

4. In a device of the class described, the 65 combination of two tubular members, one threaded to the interior of the other; a fusible plug carried by the inner member and normally positioned against a shoulder in the bore of the outer tubular member; and a 70 valve in each member.

5. In a device of the class described, the combination of two tubular members one 75 threaded to the interior of the other which is provided with an internal shoulder; a fusible plug carried by the inner member and normally abutting said shoulder; and a valve in each member.

6. In a device of the class described, the combination of two tubular members, one 80 fitted within the other and adapted to be moved endwise relatively thereto and retained in adjusted position, the outer member having an internal shoulder; a fusible plug normally abutting said internal shoul- 85 der and having a shank extending into the bore of the inner member; and a valve in each member.

7. In a device of the class described, the combination of two tubular members, one 90 fitted within the other and adapted to be moved endwise relatively thereto and retained in adjusted position, the outer member having an internal shoulder; a valve in 95 each member; a cylindrical extension to said inner member normally extending through a transverse opening in the valve of the outer member; and a fusible plug normally abutting said inner shoulder and having a shank extending into the bore of said inner member.

8. In a device of the class described, the combination of an outer tubular member having a reduced bore at one end forming a shoulder; a valve in said member rotatable 105 about an axis perpendicular to the axis of said tubular member and having a transverse cylindrical opening therein; an inner tubular member threaded to the outer member and having a cylindrical extension normally positioned in the opening in said valve thereby preventing its rotation; a fusible plug in the inner end of said inner tubular member and normally against said shoulder; and a valve in the inner tubular member be- 110 yond the outer end of the outer member.

Signed by me at 4 Post Office Sq., Boston, Mass., this 27th day of November, 1914.

JOSEPH A. RICARD.
